UNITED STATES PATENT OFFICE.

JOHN H. CALAHAN, OF PHILADELPHIA, PENNSYLVANIA.

DESIGN FOR A VALVE-DISK.

SPECIFICATION forming part of Design No. 29,982, dated January 10, 1899.

Application filed January 18, 1897. Serial No. 619,690. Term of patent 14 years.

To all whom it may concern:

Be it known that I, JOHN H. CALAHAN, a citizen of the United States, residing in Philadelphia, in the county of Philadelphia, in the State of Pennsylvania, have invented and produced a new and original Design for Valve-Disks, of which the following is a specification, reference being had to the accompanying drawing and letters of reference marked thereon, and 10 wherein is shown in perspective a valve-disk embodying my design.

As shown in the drawing, the material or leading feature of my design consists in a plain disk *a*, from one face of which is pro-

duced a vertical cylindrical stem *b*, centrally located, and in the stem is a vertically-disposed groove *c*.

I produce the design from a yielding material.

Having therefore described my invention, 20 what I claim is—

The design for a valve-disk as herein shown and described.

JOHN H. CALAHAN.
